CLAIM

The ornamental design for a television receiver, as shown and described.

DESCRIPTION

FIG. 1 is a front, left perspective view of a television receiver showing my new design;

FIG. 2 is a front, bottom, right perspective view thereof;

FIG. 3 is a front elevational view thereof;

FIG. 4 is a rear elevational view thereof;

FIG. 5 is a left side elevational view thereof;

FIG. 6 is a right side elevational view thereof; and

FIG. 7 is a top plan view thereof.

FIG. 8 is an enlarged front, left perspective view of the television receiver along the lines 8-8 and 8'-8' of FIG. 1;

FIG. 9 is an enlarged front, bottom, right perspective view of the television receiver along the lines 9-9 and 9'-9' of FIG. 2;

FIG. 10 is a cross-sectional view of the television receiver taken in the direction of lines 10-10 of FIG. 3;

FIG. 11 is a cross-sectional view of the television receiver taken in the direction of lines 11-11 of FIG. 3;

FIG. 12 is a bottom plan view of the television receiver shown without the stand portion;

FIG. 13 is an enlarged bottom plan view of the television receiver along the lines 13-13 of FIG. 12; and,

FIG. 14 is a bottom plan view of the television receiver. The evenly-dashed broken lines illustrating portions of the television receiver form no part of the claimed design. The dot-dash broken lines define the boundaries of the claimed design and form no part of the claimed design.
